(57) **CLAIM**

We claim, the ornamental design for a baffle for luminaire, as shown and described.

DESCRIPTION

FIG. 1 is a perspective view of a baffle for luminaire, showing our new design;

FIG. 2 is an end view thereof;

FIG. 3 is an opposite end view thereof;

FIG. 4 is a top plan view thereof;

FIG. 5 is a bottom plan view thereof;

FIG. 6 is a side elevation view thereof; and,

FIG. 7 is an opposite side elevation view thereof.

The jagged broken lines shown in the drawings, illustrating that the design has no specific length, form no part of the claimed design.

1 Claim, 6 Drawing Sheets
